DESIGN DYEING APPARATUS

Shepard B. Schwartz and Robert D. Blum, Jr.,
Nashville, Tenn., assignors to May Hosiery
Mills, Nashville, Tenn., a corporation of Ten-
nessee

Application November 26, 1947, Serial No. 788,185

9 Claims. (Cl. 101—115)

1

This invention relates to ornamentation and more particularly to design dyeing and apparatus for accomplishing the same.

One specific use of the invention is the application of a single or multicolored design for purposes of ornamentation to finished or fabricated textiles such as for example to hosiery or the like. The method does not pertain to woven piece goods which is printed continuously by such means as roller printing with intaglio cylinders.

Ornamentation has been accomplished in many ways including the printing of designs on piece goods and on some finished articles such as blouses, T shirts, overalls and the like. However, this type of ornamentation has either been very limited as to color and durability, or has required the use of much skilled labor or expensive machinery in the production thereof. In other words the use of a plurality of colors in a design offered substantial problems as for example in a multicolored design where the colors were applied singly they were difficult to apply in proper relation or registration.

Hosiery has also been heretofore produced with designs which have been knitted into the hosiery. This is a very costly process, requiring the use of special colored yarns in knitting, and requiring special machinery. The designs possible by this method are extremely limited due to the inherent limitations of knitting machines. Intricate and sharp designs are not possible by this method. Further, the design has not been permanent when applied by a thermoplastic or thermosetting transfer, which is inexpensive. Also, the application of a design to finished or fabricated articles of textile apparel has not been adapted to low cost quantity production, being accomplished by manual operations using the screen process or the like. The roller printing process, utilizing the same types of dyes or printing pastes as applicants' process is not adaptable to finished or fabricated articles of textile apparel, such as hosiery. Initial cost of machinery and engraving of intaglio cylinders precludes practicability of utilizing this process for fabricated textiles such as hosiery where yardage is small compared to that normally run on one design on piece goods. Also the roller process has not been adapted mechanically for the printing of fabricated articles such as hosiery but is utilized exclusively for the printing of piece goods in continuous flat form.

Applicants' apparatus has been specifically created for application of a single or multicolored design to hosiery. It is desirable that the appli-

2

cation of designs to articles such as socks be accomplished rapidly and inexpensively in order that these articles may be sold at a comparatively low price in the present highly competitive market where competition is keen, thereby precluding the manual application of such designs.

Applicants' process of applying designs is a true dyeing process in that the dye is applied to the fabric and allowed to penetrate and completely color the fibers therein. An aqueous solution of a textile coloring component, such as a vat dye, may be incorporated in the printing paste, or a pigmented oil-in-water or water-in-oil two phase emulsion, with resin binder, may be utilized. These printing pastes are well known to those skilled in the art of textile printing. Consequently, the resulting product is completely wash fast and the design will retain substantially its original brilliance and character throughout the life of the fabric.

It is an object of the invention to provide a simple and inexpensive apparatus for design dyeing and employing a multiplicity of colors which may easily be varied and in which the articles are dried prior to the application of each succeeding color.

Another object of the invention is to provide apparatus for design dyeing in which means is provided for properly initially positioning the articles relative to the apparatus and with means for automatically obtaining correct registration of the various colored portions of the design.

A further object of the invention is to provide an apparatus for design dyeing of articles particularly hosiery and utilizing flexible, fine mesh screening, the design portion of which is open and the remaining portion covered with a material impervious to the printing paste and through which design portion the dye or color paste is applied to the product.

Further objects and advantages of the invention will be apparent from the following description taken in conjunction with the accompanying drawings, wherein:

45 Fig. 1 is an elevational view of the apparatus of this invention and showing particularly the means for raising the fabric material into engagement with the dye applying means and the controls thereof;

50 Fig. 2, a plan view of the apparatus of Fig. 1 set up to apply a two-color design to opposite sides of the cuff of a sock;

Fig. 3, a plan view of the sock receiving and supporting means;

55 Fig. 4, an exploded perspective view showing

the screen carrying a design and the supporting framework therefor;

Fig. 5, a perspective view of a limit switch forming part of the control circuit with the case partially broken away and with parts omitted for greater clarity;

Fig. 6, a perspective view of the details of the foot operated control switch;

Fig. 7, a perspective view showing a sock receiving and supporting member with a sock applied thereto;

Fig. 8, a side elevation of a sock having a partially completed design in one color thereon; and,

Fig. 9, a side elevation of a sock having a complete design in two colors thereon.

With continued reference to the drawings, particularly Fig. 1, there is shown an apparatus for dyeing designs in fabrics such as hosiery having a supporting frame 10 which may conveniently comprise a plurality of upstanding legs 11 formed of angle iron or the like and having cross braces 12 to impart sufficient rigidity thereto.

Supported centrally of the framework 10 is an upstanding tubular member 13 within which is rotatably and slidably received a sleeve 14, which sleeve projects a short distance below the lower end of member 13 as indicated at 15. Sleeve 14 is in turn slidably received on a vertical rod 16 adjustably secured at its lower end in collar 17 by a set screw 18, collar 17 being supported by the lower cross-braces 12.

Secured to the upper end of sleeve 14 and supported thereby is a circular disc or table indicated generally at 19. Table 19 is provided with a plurality of boards or paddles 20 secured to the top surface thereof as by rivets 21 or other suitable securing means and extending radially beyond the circumference. These paddles are readily removable and interchangeable with various sizes and shapes, permitting the use of same equipment for any size of hosiery and the application of the design to any desired part of the article by change of shape. Boards 20 serve to receive socks or the like which may be stretched over the outer end thereof as shown in detail in Fig. 7. Boards 20 may also be provided with a colored band or the like 22 to indicate the position which the edge of the sock should occupy when placed thereover.

Located above table 19 in parallel relation thereto and supported on the upper end of rod 16 is a plate 23 which serves to support dye applying means, indicated generally at 24. Dye applying means 24 may conveniently take the form of a rectangular frame 25, the bottom opening of which is closed by a fine mesh screen 26. Screen 26 may be best formed of silk or steel wire but obviously any other suitable material may be employed. This screen must have sufficient tensile strength and resistance to wear to afford long life but must also possess sufficient flexibility to conform to irregularities in the surface of the fabric material to which a design is to be applied. The inner surface of screen 26 is coated with a material impervious to the dye being used except for a portion representing the outline of the desired design as indicated at 27 in Fig. 4. A sufficient number of dye applying means will be provided to result in a design of the desired number of colors, one dye applying means being used to apply each color.

As shown in Fig. 2, four dye applying means are secured to the plate 23 and project radially therefrom over the sock receiving boards 20, the apparatus as shown in Fig. 2 being designed to

apply a two color design to opposite sides of the cuff of a sock. Dye applying means 24 are supported at their outer ends by diagonal braces 28 extending downwardly to the legs 11 and are adjustable in a horizontal plane to provide for positioning for registration and in a vertical plane to provide for the proper pressure of the screen against the garment.

Also supported on plate 23 are a plurality of blowers 29 which are adapted to blow warm air through pipes 30 provided with nozzles 31 directed downwardly over the sock receiving boards 20 to facilitate drying of the design. In the present embodiment two blowers are shown but obviously any number in accordance with the number of colors being applied may be used.

In order to raise sock receiving boards 20 and a sock thereon into engagement with the lower surface of screen 26 there is provided a lever 32 pivoted at 33 to one of the cross braces 12. The inner end of lever 32 is provided with a yoke having rollers 34 mounted thereon, which rollers engage the shoulders 35 and 36 of a collar 37 secured to the lower end of sleeve 15 and slidably on rod 16. Lever 32 may conveniently be actuated by an air cylinder 38 secured to the frame of the machine by a bracket 39, air cylinder 38 containing a piston having a connecting rod 40 pivotally and slidably attached at 41 to the outer end of lever 32. Air may be admitted to cylinder 38 adjacent the upper end thereof through a pipe 42 to move the piston and connecting rod 40 downwardly, thus moving the inner end of lever 32, collar 34, sleeve 14, table 19 and boards 20 upwardly to engage socks on boards 20 with the lower surface of screen 26.

High pressure air may be supplied to pipe 42 and cylinder 38 through a pipe 43 leading from a high pressure source and this pipe is provided with a shut-off valve 44 which may be closed when the apparatus is not in use. Located in pipe 43 is a solenoid operated valve 45 which serves to admit air through a T-connection 46 to pipe 42. Communicating with the other outlet of the T-connection 46 is a second solenoid operated valve 47, the outlet 48 of which communicates with the atmosphere. Valve 47 and outlet 48 serve to release air pressure within the cylinder 38. In operation when it is desired to raise table 19 and boards 20, exhaust valve 47 is closed and inlet valve 45 is opened to admit air to cylinder 38 and when it is desired to lower table 19 inlet valve 45 is closed and exhaust valve 47 is opened to release air from cylinder 38.

Valves 45 and 47 are controlled by a foot operated switch 49 which, as best shown in Fig. 6, may take the form of two fixed contacts 50 and 50' and a movable contact 51. Contact 51 is pivotally mounted at 52 in the wall 53 of the casing surrounding switch 49 and contact 51 is actuated by a foot pedal 54 extending to a position convenient to the operator.

In order that valves 45 and 47 will not be actuated and the table 19 raised when not in proper position for the socks to engage screens 26, there is provided a limit switch 55 mounted beneath the table 19 and shown in detail in Fig. 5. Switch 55 may well comprise a fixed contact 56 and a movable contact 57 actuated by a shaft 58 and arm 59. Switch 55 is normally held in open position by a spring 60. In order to actuate switch 55 there is provided on the bottom of table 19 a plurality of downwardly extending pins 61, these pins being positioned inwardly of the boards 20 and there being one pin corresponding to each

board. In operation, as the table 19 and boards 20 are rotated to bring a sock beneath the screen 26 one of the pins 61 will contact the curved portion 62 of arm 59 on the switch 55 to close the switch.

In order that the valves 45 and 47 will be controlled in such manner that valve 47 is open and valve 45 is closed in the up position of pedal 54 and that valve 47 will be closed and valve 45 open in the down position of pedal 54, the circuit for control of these valves is so arranged that fixed contact 50 together with movable contact 51 controls the application of voltage from a source of electrical current provided by cable 63 to the valve 47 whereby when the pedal 54 is in the up position valve 47 will be energized and remain open. Fixed contact 50 in conjunction with movable contact 51 is connected in such manner that voltage from the cable 63 will be applied to energize valve 45 and open the same when the pedal 54 is depressed. Limit switch 55, described above, is connected in series with the source of electrical current, valve 45 and fixed contact 50 in order that the table 19 will not be raised unless it is located in proper position since if the limit switch 55 is open and the pedal 54 is depressed, no voltage may be applied to the valve 45, the application of voltage thereto only being possible when the switch 55 is in closed position. It is therefore apparent that means has been provided to raise and lower table 19 in accordance with the desires of the operator by merely actuating pedal 54 and that further means has been provided to insure that the table 19 will be in proper position prior to raising thereof. Switch 64 is provided to open the circuit in the source of electrical current during periods in which the machine is out of operation.

In order to insure that paddles 20 and socks mounted thereon will be in proper position to receive an impression from the screens 26 and to further insure that proper registry of the various colored portions of the design will be obtained, there is provided in the table 19 a series of apertures 65, there being one aperture for each of the boards 20. Secured to the plate 23 and extending downwardly therefrom is a tapered pin 66 which is so positioned as to enter one of the apertures 65 when the table 19 is properly positioned and to accurately locate boards 20 and the socks carried thereby to obtain perfect registry of the designs and it will be obvious that should the table 19 be slightly out of alignment that upon raising of the same, pin 19 will enter hole 65 and move the table into perfect alignment.

In the operation of applying a design to a sock an operator places the sock on board 20 at station A as shown in Fig. 2 with the sock occupying a position as indicated by the band 22 on board 20. Table 19 and boards 20 are rotated in a clockwise direction until the sock placed in position at station A is located under the screen 26 at station B. At this time foot pedal 54 is depressed to raise the sock into engagement with the lower surface of screen 26 whereupon a squeegee 67 is drawn lengthwise of the screen to force dye deposited thereon through the design portion 27 and apply this design to the sock. The design applied at station B may well be the first color of a design, as illustrated in Fig. 8. Upon completion of the operation at station B, the table 19 is moved clockwise to bring the sock just dyed beneath the nozzle 31 of pipe 30 at station C whereupon warm air passes over the design to dry the dye deposited on the sock. At the same

time, of course, a design is applied to the following sock at station B. The sock at station C is next moved to station D whereupon the remaining color of the two color design is applied in a manner similar to that at station B, resulting in a complete design as illustrated in Fig. 9.

At the completion of the operation at station D, the sock is moved to station E at which point an operator reverses the sock on board 20 to bring the lower side uppermost. The sock is then moved around to station F, at which point the first color of the design is applied, this color being dried at station G and the final color being applied at station H, the completed sock being removed at station I. It will be obvious that the operation at stations F, G, and H is identical to that at stations B, C and D, but if desired different designs may be applied to opposite sides of the sock or a design of only one color or two or more colors might be applied to either side of the sock.

There is thus provided by this invention an apparatus for applying a design to a fabricated, textile fabric such as a sock in a simple and expeditious manner and one which requires no skilled labor, since the manual operations required in performing the dyeing process on this apparatus are merely routine and consist in applying and removing the sock and in drawing the squeegee over the screen to force dye there-through.

It will be obvious to those skilled in the art that various changes may be made in the invention without departing from the spirit and scope thereof and therefore the invention is not limited by that which is shown in the drawings and described in the specification but only as indicated in the appended claims.

What is claimed is:

1. Apparatus for design dyeing of fabric articles comprising in combination a frame, a horizontal table rotatably and slidably mounted on said frame, article receiving boards secured to said table and extending radially therefrom, means on said boards to facilitate the positioning of articles thereon at the proper location, a plurality of dye applying means supported above said boards, said dye applying means comprising a rectangular frame, a screen secured to the lower surface of said frame, said screen being coated with a material impervious to the dye except in a portion forming the outline of the design to be applied, a squeegee disposed in said frame and contacting the upper surface of said screen whereby movement of said squeegee over said screen will force dye through the open design portion thereof, means for raising said boards and articles received thereon into engagement with the lower surface of said screen, said last named means comprising a pneumatic cylinder and piston, electric control means for said raising means comprising solenoid operated valves, a foot control therefor and limit switch means rendering said valves inoperative when said boards are improperly positioned to engage said screens, an aperture in said table corresponding to each board, a tapered pin constructed and arranged to enter said aperture upon raising of said table whereby said boards will be accurately positioned to obtain proper registration of said design on said article, and means comprising a blower and heating element constructed and arranged to direct warm air onto said design subsequent to application thereof whereby said

design will be dried prior to application of another color or removal from the apparatus.

2. Apparatus for design dyeing of fabric articles comprising in combination a frame, a horizontal table rotatably and slidably mounted on said frame, article receiving boards secured to said table and extending radially therefrom, means on said boards to facilitate the positioning of articles thereon at the proper location, a plurality of dye applying means supported above said boards said dye applying means comprising a rectangular frame, a screen secured to the lower surface of said frame, said screen being coated with a material impervious to the dye except in a portion forming the outline of the design to be applied, a squeegee disposed in said frame and contacting the upper surface of said screen whereby movement of said squeegee over said screen will force dye through the open design portion of said screen, means for raising said boards and articles received thereon into engagement with the lower surface of said screen, said last named means comprising a pneumatic cylinder and piston, electric control means for said raising means comprising solenoid operated valves, a foot control therefor, and limit switch means rendering said valves inoperative when said boards are improperly positioned to engage said screens, an aperture in said table corresponding to each board, a tapered pin constructed and arranged to enter said aperture upon raising of said table whereby said boards will be accurately positioned to obtain proper registration of said design on said article.

3. Apparatus for design dyeing of fabric articles comprising in combination a frame, a table rotatably and slidably mounted on said frame, article receiving boards secured to said table and extending radially therefrom, dye applying means supported above said boards said dye applying means including a screen impervious to the passage of dye therethrough except in a portion forming the outline of the design to be applied, means constructed and arranged to force dye through the design portion of said screen, means for raising said articles into engagement with the surface of said screen, an electrical circuit including a foot operated switch for controlling the operation of said raising means, a limit switch in said circuit operable for rendering said raising means operative when said boards are properly positioned with relation to said screen, said limit switch comprising a fixed contact and a movable contact, an actuating arm operatively associated with said movable contact, a pin secured to said table corresponding to each board constructed and arranged to engage said actuating arm to close said contacts upon movement of said boards and articles carried thereby to screen engaging position, and means constructed and arranged to dry said dye subsequent to the application thereof to said articles.

4. An apparatus for design dyeing of fabric articles comprising in combination a frame, a table rotatably and slidably mounted on said frame, article receiving boards secured to said table and extending radially therefrom, a plurality of dye applying means supported above said boards said dye applying means including a screen impervious to the passage of dye therethrough except in a portion forming the outline of the design to be applied, means constructed and arranged to force dye through the design portion of said screen, a fluid pressure cylinder,

a piston slidably received in said cylinder, a lever connected to said piston and said table whereby said table may be raised or lowered by movement of said piston, a conduit communicating with a source of fluid under pressure, a solenoid operated valve in said conduit constructed and arranged to control the admission of fluid to said cylinder, a fluid outlet communicating with said cylinder, a solenoid operated valve in said outlet constructed and arranged to control the release of fluid from said cylinder, an electrical circuit including said solenoids and a foot operated switch for controlling the operation of said valves, and means in said circuit for rendering said valves operative when said boards are properly positioned with relation to said screens.

5. An apparatus for design dyeing of fabric articles comprising in combination a frame, a table rotatably and slidably mounted on said frame, article receiving boards secured to said table and extending radially therefrom, dye applying means supported above said boards, said dye applying means including a screen impervious to the passage of dye therethrough except in a portion forming the outline of the design to be applied, means constructed and arranged to force dye through the design portion of said screen, means for raising said articles into engagement with the surface of said screen, a foot pedal operatively connected with said raising means for controlling the operation thereof, means operatively connected with said raising means and controlled by said table for rendering said raising means operative when said boards are properly positioned with relation to said screens, means operatively associated with said table to accurately position said boards upon movement thereof relative to said screens, and means constructed and arranged to dry said dye subsequent to the application thereof to said articles.

6. Apparatus for design dyeing of fabric articles comprising in combination a frame, a table rotatably mounted on said frame, article receiving members secured to said table and extending radially therefrom, dye applying means supported above said members, said dye applying means including a screen having a portion forming the outline of the design to be applied, means constructed and arranged to force dye through the design portion of said screen, means for moving said members toward said screens, means for controlling the operation of said moving means, and means operatively connected with said controlling means and actuated by said table for rendering the controlling means operative when said members are properly positioned relative to said screen.

7. Apparatus for design dyeing of fabric articles comprising in combination a frame, a table rotatably mounted on said frame, article receiving members secured to said table and extending radially therefrom, dye applying means supported above said members, said dye applying means including a screen having a portion forming the outline of the design to be applied, means constructed and arranged to force dye through the design portion of said screen, means for producing contact between said articles and the surface of said screen, means for controlling the operation of said contact producing means, and means operatively connected with said controlling means and actuated by said table for rendering the controlling means operative when said members are properly positioned relative to

said screen, and means for accurately positioning said members relative to said screen.

8. An apparatus for design dyeing of fabric articles comprising in combination a frame, means on said frame to support said articles, dye applying means supported adjacent said article supporting means, means to move said article support relative to said dye applying means, control means operatively connected with said moving means and controlled by said article supporting means for rendering said moving means operative when said article supporting means is properly positioned relative to said dye applying means, means constructed and arranged to accurately position said article support with respect to said dye applying means upon relative movement thereof, and means constructed and arranged to dry said dye subsequent to the application thereof to said articles.

9. An apparatus for design dyeing of fabric articles comprising in combination a frame, means on said frame to support said articles, dye applying means supported adjacent said article supporting means, means to move said article

support into engagement with said dye applying means, control means operatively connected with said moving means and controlled by said article supporting means to render said moving means operative when said article supporting means is properly positioned relative to said dye applying means, and means constructed and arranged to dry said dye subsequent to the application thereof to said articles.
